COMBINED TISSUE DISPENSER AND UTILITY DRAWER

Sol Esner, 710 E. Sharpnack St., Philadelphia, Pa.

Filed July 14, 1964, Ser. No. 80,874

Term of patent 14 years

(Cl. D52—2)

Fig. 1

I claim:

The ornamental design for a combined tissue dispenser and utility drawer, as shown and described.
